D6,801

UNITED STATES PATENT OFFICE.

CHARLES W. ARMSTRONG, OF DETROIT, MICHIGAN.

DESIGN FOR ADVERTISING-DESK.

Specification forming part of Design No. **6,801**, dated August 12, 1873; application filed June 27, 1873.

To all whom it may concern:

Be it known that I, CHARLES W. ARMSTRONG, of the city of Detroit, county of Wayne and State of Michigan, have invented a Design for an Ornamental Advertising-Desk, of which the following is a specification:

The nature of my design is fully represented in the accompanying photographic illustration, to which reference is made.

My design is for an ornamental writing-desk for commercial rooms of hotels and other public places of resort; and embraces a double desk upon proper legs, supporting upon small posts a boxed riser with sloping faces on each

side, subdivided into panels. At the basis of this riser are small channels, and surmounting this riser are two double-faced ornamental shields or panels, all as shown more particularly in the photograph accompanying this application; and

I claim as new, and as my invention—

The design for an advertising-desk, as shown and described.

C. W. ARMSTRONG.
